(57) CLAIM

The ornamental design for ball rack, as shown and described.

DESCRIPTION

FIG. 1 is a front perspective view of a ball rack according to a first embodiment and showing the top rack in a level position;

FIG. 2 is a front view thereof;

FIG. 3 is a rear view thereof;

FIG. 4 is a right side view thereof, the left side view being a mirror image;

FIG. 5 is a top view thereof;

FIG. 6 is a front view of a ball rack showing the top rack in a sloped position;

FIG. 7 is a front perspective view of a ball rack according to a second embodiment and showing the top rack in a level position;

FIG. 8 is a front view thereof;

FIG. 9 is a rear view thereof;

FIG. 10 is a right side view thereof, the left side view being a mirror image;

FIG. 11 is a top view thereof;

FIG. 12 is a front view of a ball rack showing the top rack in a sloped position;

FIG. 13 is a front perspective view of a ball rack according to a third embodiment and showing the top rack in a level position;

FIG. 14 is a front view thereof;

FIG. 15 is a rear view thereof;

FIG. 16 is a right side view thereof, the left side view being a mirror image;

FIG. 17 is a top view thereof; and,

FIG. 18 is a front view of a ball rack showing the top rack in a slanted position.

The broken lines shown in the drawings illustrate portions of the article that form no part of the claimed design.

The second and third embodiments of the ball rack are shown with symbolic breaks in its width and height. The appearance of any portion of the article between the break lines forms no part of the claimed design.
